[57] ABSTRACT

A ski binding including a sole plate to which a ski boot is secured. The sole plate is supported on a ski plate for rotatable movement of the sole plate about forward pitch and yaw axes located beneath a skier's center of gravity. Means is provided for preventing movement of the sole plate relative to the ski plate about these axes when subjected to pitching and yawing torques occurring during normal maneuvers and for allowing said sole plate to be released for settable abnormal (excessive) pitching and/or yawing torques.

SKI BINDING

BACKGROUND OF THE INVENTION

1. Field of the Invention

Safety ski binding

2. Description of the Prior Art

Skiing is an extremely popular sport and is enjoyed by both young and old throughout the world. The number of skiers in the last 20 years has increased approximately by 3,000 percent and it is estimated that approximately three and one-half million Americans now ski.

With this great popularity of skiing there has been increasing attention directed to the injuries that have in the past been an inherent part of skiing such as bone fractures, muscle sprains, dislocated shoulders, torn ligaments, bruises, etc.

Standard skiing equipment now includes skis, ski boots and bindings for securing the ski boots to the skis.

Originally, the bindings consisted of metal clamps attached to the skis which were appropriately called "bear trap" bindings. The main characteristic of this type of binding was that once the skier inserted his boot into the metal clamp on the ski there was virtually no way to effect release ("release" is used to indicate automatic separation of a boot from a ski upon occurrence of abnormal torques). As time passed release bindings were developed which theoretically were designed to allow a boot to disengage from a ski during a fall and thereby minimize the chances of serious injury. A particular criticism of many prior art bindings was that the bindings allowed premature release. Thus, many times a skier found himself disengaged from his skis when he least expected it, which of course was dangerous. On the other hand many times the bindings did not function properly to effect release when required which was also dangerous.

Originally, ski boots were relatively soft and many skiing injuries involved ankle fractures of the lateral or fibular malleolus which became known as skier's fractures. A further type of injury that was associated with soft ski boots was a spiral fracture of the shaft of the tibia (the thick leg bone).

Most ski boots are now made of rigid materials with the consequence that many of the injuries suffered by skiers using these boots involves transverse fractures of the distal end of the tibia. These injuries can be very severe and many times involve compound fractures which require months of healing.

It is of course to be appreciated that no matter what type of boot is used, if the binding effects release at the proper time and otherwise works properly most injuries can be avoided.

The falls that a skier can undergo can be categorized into two varieties. The first type of fall is known as the unweighted fall and in this type of fall the weight of the skier is not imposed on the skis during the fall. This type of fall can occur when a skier's skis ride up a mogul (a hard mound of snow), the skier loses his balance and falls on his side. The force from the weight of the skier is not transferred to the skis and is received on the part of the body of the skier which hits the snow and unless release is effected the skis can become trapped in the snow and cause serious injury.

In a weighted fall the weight of the skier is exerted downwardly on the skis and usually occurs in deep snow. In this type of fall very frequently the skier's leg turns in one direction while his weight still is supported by his feet. Unless the binding releases serious injury can and does result.

Weighted and unweighted falls occur, in part, as a result of excessive pitching (both forward and rearward) and yawing. Forward pitching is defined as the rotational motion of the ski boots relative to the skis so as to increase the distance from the heels of the boots to the ski surfaces as compared to the distance from the toes of the boots to the ski surfaces. Forward pitching by the skier is caused by an abnormally high forward pitching torque being applied to the ski bindings. Forward pitching torque is created when the skier's body is rotated about his feet (held fast in the boots) in a forward direction and a sufficient amount of such rotation places a strain on his knees since the physiological makeup of a human being does not allow a person's knees to bend forwardly to relieve strain. A sufficient amount of forward pitching torque without release severely strains the ankles since the heels are captive in the boots and serious injuries can result therefrom.

In addition to the danger of serious injury from forward pitching torque without release, injury can also result from rearward pitching torque without release, with rearward pitching being defined as the rotational motion of the ski boots relative to the skis so as to increase the distance from the toes of the boots to the ski surfaces as compared to the distance from the heels of the boots to the ski surfaces. Rearward pitching by the skier is caused by an abnormal rearward pitching torque being applied to the ski bindings after the knees have bent rearwardly as far as circumstances permit. When rearward pitching torque occurs the skier's body is rotated in a rearward direction about his feet which are held fast in the ski boots and a sufficient amount of said rotation without release severely strains the skier's ankles since his feet are captive in the boots.

Serious injury can also result when more than a predetermined amount of yawing torque occurs without release (while the skier's boots are secured to his skis so as to move therewith), with yawing being defined as the rotational movement of the ski boots with respect to the longitudinal axis of the skis while the boot sole planes remain parallel to the ski surface planes. Yawing results from the application of an abnormal yawing torque being applied to the ski bindings. Yawing torque without release can engender twisting of the ankles, knees and hips and legs.

Most ski bindings are designed to enable boots to be released when excessive pitching and/or yawing occurs. With many prior art ski bindings it is not possible to set the torque release point for pitch release independently of the torque release point for yaw release. This is undesirable since, practicably, for safe skiing it is necessary to have yaw release occur at a different torque than that at which pitch release occurs.

With many prior art ski bindings frictional surfaces exist between the ski boot and ski so that release settings are unreliable, i.e., will occur at different values under different prevailing conditions. As an example with some prior art ski bindings the boot sole contacts the skier's ski plate in its entirety and static and kinetic frictional forces due to body weight and acceleration

forces on rough terrain can easily double the torque required to effect release of the ski boot from the ski.

A further drawback of having a boot sole contact with the ski or a ski plate is that as a result of static and kinetic friction therebetween torques are not transmitted to the binding release means to effect release.

Additionally, with most prior art ski bindings means is provided for securing the ski boot to the ski at the toe and heel of said boot. This severely limits the freedom of motion of the boot toe relative to the ski which impairs the effective operation of the binding release means. With some prior art ski bindings which use a toe piece that operates a release means, a high impact on said toe piece is required to effect release. Very frequently the force required to effect release for women skiers is above the women's injury threshold which may account, in part, for the higher injury rate of women. An additional drawback of having a toe piece obstruction in the front of the boot is that the toe piece obstruction blocks forward movement of the boot relative to the ski during a fall, after release, and causes the skier's ankle to assume an acute dorsiflexion position. When this occurs the ankle becomes rigid and ankle and joint injuries often result.

Other drawbacks generally associated with many prior art ski bindings are that the bindings are not of rugged construction and require constant attention. Additionally, with many bindings different yaw torques are required to effect release from a clockwise yaw and a counter clockwise yaw which is of course undesirable.

SUMMARY OF THE INVENTION

1. Purposes of the Invention

It is an object of the present invention to provide an improved ski binding and specifically one that will overcome the disadvantages heretofore noted.

Another object of the present invention is to provide an improved ski binding wherein the effects of frictional forces on release settings are minimal.

Still a further object of the present invention is to provide an improved ski binding wherein the effects of the skier's weight and force couples on release settings are minimal.

Another object of the present invention is to provide a ski binding having the forward pitching and yawing axes in close proximity to one another.

A still further object of the present invention is to provide an improved ski binding having release means minimally effected by frictional forces, the presence or absence of the skier's weight, force couples and acceleration forces.

Yet another object of the present invention is to provide an improved ski binding having means for varying the amount of forward and rearward pitching torque required to effect release.

Still another object of the present invention is to provide an improved ski binding having means for varying the amount of yawing torque required to effect release.

Yet another object of the present invention is to provide an improved ski binding having means for varying the torque required to effect release from forward and rearward pitching independently of the torque required to effect release from yawing.

A further object of the present invention is to provide a ski binding having means for varying the torque re-

quired to effect release from yawing independently of the torque required to effect release from forward and rearward pitching.

An ancillary object of the invention is to provide an improved ski binding having means to concurrently selectively change the pitch and yaw settings and means to change the ratio between said two settings.

A further object of the present invention is to provide a ski binding having an improved runaway lanyard that enables a ski to clear both the toe and heel of a boot.

Yet another object of the present invention is to provide an improved lanyard secured to the approximate center of the sole of a ski boot and to a ski.

Other object of the invention will be pointed out hereinafter.

2. Brief Description of the Invention

According to one aspect of the present invention the foregoing and other objects are achieved by low friction means for supporting a ski boot sole plate in spaced relation to a ski.

A release means is provided for enabling said ski boot sole plate to be released from the ski upon the occurrence of variably settable pitching and yawing torques. One part of runaway lanyard is secured to the sole plate and a part spaced therefrom is secured to the ski.

During controlled (normal) skiing (where the skier is in control of the orientation of his body and neither pitching in either a forward or rearward direction nor yawing more than predetermined amounts) the weight of the skier is supported by the low friction means. If the skier should pitch forwardly or rearwardly and create a forward or rearward pitching torque more than the amounts allowed by the release means, release is effected. The lanyard prevents the ski from moving free of the boot.

A sufficient amount of yawing torque causes the sole plate to yaw and if the torque is sufficiently high release is effected.

It should be noted that the low friction means minimizes the effects of friction and the effects of the skier's weight on the various release means.

BRIEF DESCRIPTION OF THE DRAWINGS

In the drawings wherein like elements in the different FIGS. are represented by the same reference numerals:

FIG. 1 is an exploded perspective view of a preferred embodiment of the ski binding of the present invention;

FIG. 2 is a top plan view of the ski binding of the first embodiment securing a ski boot to a ski;

FIG. 2a is an enlarged horizontal sectional view of the hinge plate and hinge post of the first embodiment of the ski binding showing one way that the hinge plate and hinge post can cooperate with one another;

FIG. 2b is an enlarged vertical sectional view of the hinge plate and hinge post of the first embodiment of the ski binding showing one way that the hinge plate and hinge post can cooperate with each other;

FIG. 3 is a sectional view taken substantially along the line 3-3 of FIG. 2;

FIG. 4 is an enlarged top plan view of a segment of the pitch and yaw release mechanism of the first embodiment of the ski binding;

FIG. 5 is a sectional view taken substantially along the line 5-5 of FIG. 4;

FIG. 6 is a top plan view showing the first embodiment of the ski binding immediately after yaw-induced release;

FIG. 7 is a vertical sectional view showing the first embodiment of the ski binding immediately after forward pitch-induced release;

FIG. 8 is a vertical sectional view showing the first embodiment of the ski binding immediately prior to rearward pitch-induced release;

FIG. 9 is an exploded perspective view of a second embodiment of the ski binding of the present invention;

FIG. 10 is a top plan view of a second embodiment of the ski binding securing a ski boot to a ski;

FIG. 10a is an enlarged horizontal sectional view of the hinge plate and hinge post of the ski binding of the second embodiment showing how these elements cooperate with one another;

FIG. 11 is a sectional view taken substantially along the line 11—11 of FIG. 10;

FIG. 12 is a top plan view showing the second embodiment of the ski binding immediately prior to yaw-induced release;

FIG. 13 is a vertical sectional view showing the second embodiment of the ski binding immediately prior to forward pitch-induced release;

FIG. 14 is a top plan view of a third embodiment of the ski binding of the present invention;

FIG. 14a is an enlarged horizontal sectional view of the hinge plate and hinge post of the third embodiment of the ski binding;

FIG. 15 is a sectional view taken substantially along the line 15—15 of FIG. 14;

FIG. 16 is a top plan view showing the third embodiment of the ski binding immediately after yaw-induced release;

FIG. 17 is a vertical sectional view showing the third embodiment of the ski binding immediately prior to forward pitch-induced release;

FIG. 18 is a top plan view of a fourth embodiment of the ski binding of the present invention securing a ski boot to a ski;

FIG. 19 is a sectional view taken substantially along the line 19—19 of FIG. 18;

FIG. 20 is a top plan view of the fourth embodiment of the ski binding immediately after yaw-induced release;

FIG. 21 is a vertical sectional view showing the fourth embodiment of the ski binding immediately after forward pitch-induced release;

FIG. 22 is an enlarged top plan view of the pitch and yaw release mechanism for the third and fourth embodiments of the ski binding;

FIG. 23 is an enlarged side view of the pitch and yaw release mechanism of the third and fourth embodiments of the ski binding;

FIG. 24 is an enlarged sectional view taken substantially along the line 24—24 of FIG. 14; and

FIG. 25 is an exploded perspective view of a portion of the pitch and yaw release mechanism used in the third and fourth embodiments of the ski binding.

DESCRIPTION OF THE PREFERRED EMBODIMENTS

In FIGS. 1 through 8 of the drawings a first embodiment of a ski binding according to the present invention is shown for securing a ski boot 10 to a ski 12. Ski

boot 10 is a conventional boot made of substantially rigid material and includes a rigid sole 14. A rigid metal sole plate 16 is provided to which boot 10 is normally secured in a fashion such that it can be easily removed by a skier at his option. For this purpose there is provided a boot nose catch 18 located at and permanently secured to the front portion of sole plate 16 and a manually releasable fastening means 20. Fastening means 20 includes a heel dog 22 which can be manipulated to exert a downward force on the heel portion of sole 14 and adjustable length arms 24 rotatably secured to said stop and flanking opposite sides of sole 14. The ends of arms 24 remote from stop 22 are bent inwardly and sets of registered holes are located in the sides of sole plate 16 (FIG. 1) into which said inwardly bent portions can be inserted, the particular holes selected depending on the length of the boot. As will be apparent to those knowledgeable in the art fastening means 20 is conventional for securing a ski boot to a sole plate and it is to be understood that the use of the particular fastening means described herein is for purposes of illustration only and not of limitation.

Depending downwardly from the rear of sole plate 16 is a flange 26 and bottom surface of which is spaced a short distance from the top of a metal ski plate 28 that is rigidly fastened to the upper surface of ski 12. Side flanges extend downwardly along the edges of sole plate 16 from flange 26 towards the front of said sole plate and decrease in height going towards the front of sole plate 16. A U-shaped strip 17 of readily compressible resilient filler material, e.g., foam rubber or foamed resilient polyurethane, is secured to the upper surface of ski 12 at the front and sides thereof and has its maximum height beneath the front of sole plate 16 and decreases in height towards the rear thereof. Filler strip 17 along with the side flanges depending from sole plate 16 prevents snow and/or ice from compacting and/or forming between ski 12 and sole plate 16, the presence of which would limit the freedom of movement of the sole plate relative to the ski plate.

Permanently and rigidly secured to sole plate 16 on the bottom thereof is a downwardly extending rigid metal hinge plate 30 which includes a forward flat top surface tip 32 that is inclined upwardly and rearwardly and defines a forwardly opening acute angle with a plane parallel to the sole plate. Depending downwardly from tip 32 is a semi-cylindrical upright front nose surface 34. A flat front bottom surface 36 extends rearwardly from the bottom of nose 34 and an upwardly and rearwardly sloping back bottom surface 38 extends away from surface 36. The axis of curvature C of nose 34 which passes through top surface tip 32 defines a yaw axis. Hinge plate 30 is substantially triangular in plan and includes rearwardly flared side surfaces 30a and 30b.

A small, e.g., three-eighths inch by three-eighths inch step bearing 40 is located on the bottom of surface 36 and normally is in face to face contact with ski plate 28. The top of hinge plate 30 above surface 32 is secured to sole plate 16 in a fashion such that bearing 40 is approximately beneath the center of gravity of a skier wearing boot 10.

An upstanding rigid metal hinge post 42 is secured to ski plate 28. Hinge post 42 includes a V-shaped rearwardly facing recess 46 that is defined by walls 48, 50, 52 and 54 with walls 48 and 52 and walls 50 and 54 being respectively in transverse registry with each

other. Walls 48 and 52 are the same height. Walls 50 and 54 similarly are equal in height with the latter two walls (50,54) having a slightly greater height than walls 48 and 52. Recess 46 is bisected by the central longitudinal axis of the ski.

A rounded wall 56 connects walls 50 and 54 at the apex of recess 46. An overhang 57 extends towards the rear of ski 12 from the upper portion of wall 56. The bottom of overhang 57 consists of a flat surface sloped to approximately match the slope of surface tip 32.

The entry angle of recess 46 defined by walls 48 and 52 is considerably larger than the bearing angle of said recess defined by walls 50 and 54 with the amount of excess not being material to the proper functioning of the binding. The bearing angle between walls 50 and 54 is, in turn, greater than the inclined angle between side surfaces 30a and 30b of hinge plate 30 by an amount sufficient for the plate to swing to either side enough to release in yaw without surfaces 30a and 30b bearing on walls 50 and 54. Overhang 57 extends a small distance over surface tip 32, e.g., one-thirty second of an inch rearwardly of the front of nose 34, to allow said hinge plate to cam out from under and thereby disengage from post 42 upon rearward movement of plate 16, occasioned by undue rearward pitching torque, to effect release. The width of recess 46 at the rear of the entry angle is slightly, e.g., a few thousandths of an inch, wider than the width of nose 34 so that the nose can be seated for rotation about yaw axis C in the bearing angle if tolerances permit as will hereinafter be described.

Secured to the front of hinge post 42 is a lanyard support which consists of a hoop 58 that extends through an opening in hinge post 42 so as to be pivotable about said hinge post. A second lanyard support includes a pin 60 between a pair of posts secured to the bottom of sole plate 16 above hoop 58. A flexible lanyard 62 has its opposite ends secured to hoop 58 and pin 60. The lanyard is long enough to let the ski clear the heel or toe of boot 10 subsequent to release. The lanyard is slidably engaged between its ends by an elastic restraint E, e.g., a rubber band, that is anchored to a post 63 on ski plate 28 near but in back of strip 17. The restraint pulls the center of the lanyard forwardly, causing the lanyard to assume an almost flat V-shaped configuration as long as the hinge plate is in the recess of the hinge post.

Secured to ski plate 28 and positioned slightly to the front of the rearmost portion of sole plate 16 is a bearing block 64 which extends transversely across plate 28 and includes a transverse bearing surface 66 parallel to the ski.

A partition 70 extends transversely across the bottom of sole plate 16 parallel to and forward of flange 36 and in close proximity thereto. Journalled by partition 70 and flange 26 in a common plane parallel to the sole plate are shafts 72 and 74 with said shafts being slightly inclined with respect to each other and intersecting each other if forwardly extended through yaw axis C. Freely rotatable about shaft 72 between partition 70 and flange 26 is a roller 76. Means is provided for preventing said roller from moving axially relative to shaft 72. Secured to shaft 74 and freely rotatably thereabout between partition 70 and flange 26 is a second roller 78 with rollers 76 and 78 being of equal size. Means is provided for preventing roller 78 from moving axially along shaft 74. Rollers 76 and 78 have the same diam-

eter, are equally spaced from partition 70 and flange 26 and are arranged so that the bottom portion of each roller extends slightly beyond the bottom of the flanges which depend from the sides of sole plate 16 adjacent each of said rollers. If desired, a bottom plate 80 can extend between the bottom of partition 70, flange 26 and the base of the flanges depending from sole plate 16 and include a channel 82 through which the bottom portion of rollers 76 and 78 extend. Rollers 76 and 78 ride on surface 66 and form therewith a low friction bearing at the rear of sole plate 16 for turning movement of sole plate about axis C.

Secured to flange 26 is a pitch and yaw release plate 84 with the top of said plate coplanar with the top of sole plate 16. A projection 90 extends rearwardly from a rear surface 86 of pitch and yaw release plate 84 and is symmetrically positioned with respect to the lateral edges of said plate. Positioned near the top of projection 90 on the rear thereof is a transverse surface 96 which extends perpendicularly downwardly from the upper flat surface of plate 90 to a ramp 98 that is in fore and aft alignment with nose 34. Ramp 98 extends rearwardly and downwardly to a depending vertical surface 100. Ramp 98 is relatively narrow and is slightly transversely arcuate with its center of curvature at axis C.

Located beneath vertical surface 100 and offset forwardly therefrom is yaw socket 102 which is open at its bottom and is V-shaped in plan with slightly arcuate vertical walls 102a and 102b. As will be seen in FIG. 5 socket 102 has a slight forward downward inclination for a reason that will soon be readily apparent and socket 102 is bisected by a fore and aft plane passing through the center of hinge post 30. Socket 102 and ramp 98 are located vertically between the top and bottom of hinge post 30.

Secured to the rearmost portion of ski plate 28 is a housing 104 which has a cross section substantially similar to that of an inverted "U." Housing 104 includes an upright front face 106 and an upright rear face 108. Openings 110 and 112 are located on front face 106 while openings 114 and 116 are located on rear face 108. Openings 110 and 114 have the same cross section and are in longitudinal registry with one another. Located within housing 104 are vertically stacked sleeves 118 and 120. Sleeves 118 and 120 are defined by circular walls which extend longitudinally from one face of housing 104 to the other face thereof. The rear ends of sleeves 118 and 120 are internally threaded for a reason that will soon be readily apparent.

Annular flanges 122 are provided near front face 106 of housing 104 being located in bottom and top sleeves 118 and 120, respectively. Tubular oil impregnated bearings 124 and 126 are located in the front portions of sleeves 118 and 120. Face 106 of housing 104 is tapered forwardly about openings 110 and 112 with said tapers and flanges 122 captively holding said bearings against axial movement in their respective sleeves.

Extending forwardly of top opening 112 is a nipple-shaped pitch pin 128 with said pin being circular in transverse cross section and having a flat free end. The base of pin 128 is integral with a ferrule 130 having a rear rim 132. Ferrule 130 slides in top bearing 124. Rim 132 is so positioned that when pin 128 extends forwardly from top opening 112 somewhat beyond the position the pin is held by ramp 98 under a condition of no forward pitch, front rim 132 abuts flange 122 to pre-

vent forward movement of pin 128 relative to housing 104.

A top plug 136 is provided and located at the forward end thereof is a spring retaining collar 138 which is externally threaded. The externally threaded portion of spring retaining collar 138 is in threaded engagement with the threads at the rear end of top sleeve 120. A partition 139 extends inside collar 138 across the rear end thereof. The rear end of plug 136 includes a screw-driver receiving notch 140.

A compression coil spring 142 is located in top sleeve 120 and includes two ends with one end in abutment with rim 132 and the other end in abutment with partition 139 of collar 138.

Structure identical to the pin, spring and plug described in connection with top sleeve 120 is similarly located and arranged with respect to bottom sleeve 118 and in the interest of brevity a description of said structure is eliminated except for noting that pin 146 which is a yaw pin extends further forwardly away from face 106 than pin 128 and is rounded on its free end.

With zero tolerances for hinge plate 30 and hinge post 42, hinge plate 30 is received in hinge post recess 46 with top surface tip 32 in face to face bearing contact with sloped bottom surface of overhang 57, sides of nose 34 in dual linear bearing contact with walls 50 and 54 and step bearing 40 in face to face bearing contact with ski plate 28.

It is of course to be appreciated that zero tolerances for a mass produced item such as a ski binding are impossible economically to achieve and thus there are two possible positions of hinge plate 30 in post 42. In one such position top surface tip 32 contacts bottom of overhang 57 with bearing 40 in contact with ski plate 28 and with one or the other side of nose 34 in contact with an adjacent wall 50 and 54 of the bearing angle. It is to be understood that in such position with normal manufacturing tolerances there will be a slight essentially imperceptible amount of side play such that nose 46 of hinge plate 30 can move laterally by a tiny amount in recess 46. The second position of hinge plate 30 in recess 46 occurs when the height of nose 34 is slightly less than the distance from ski plate 28. Then the insertion of hinge plate 30 into recess 46 results in both sides of nose 34 rotatably contacting adjacent walls 54 and 50, respectively, and thus limiting the forward movement of hinge plate 30. Bearing 40 is in contact with ski plate 28 and tip 32 barely clears the bottom of overhang 57. There may be a slight imperceptible amount of vertical play. The three zone contacts of the two positions may wear in use into a four zone contact which is an amalgam of the two positions.

In the following description of the use of the preferred ski binding just described reference will be made to the operation of one such binding for purposes of brevity, keeping in mind that in normal use a skier uses identical bindings for each of his skis.

The ends of lanyard 62 are secured to the hoop 58 and pin 60. Sole plate 16 is positioned so that hinge plate 30 is received within recess 46 with bearing 40 resting on ski plate 28. As previously described, depending upon the tolerances of the hinge plate and hinge post, either one of two specified conditions (or after wear both) will occur with bearing 40 contacting ski plate 28 in both conditions. With sole plate 16 positioned so the hinge plate is located as just described rol-

lers 76 and 80 are in transversely movable low friction contact with bearing surface 66.

Sole plate 16 is positioned parallel to ski plate 28 by inserting hinge plate 30 in the hinge post recess as just described and forcing the rear of the sole plate down until pitch pin 128 snaps on to ramp 98 so the yaw pin is received in yaw socket 102 and pitch pin 128 rests on ramp 98. Yaw pin 146 is in contact with each of walls 102a and 102b. Pitch pin 128 rests on ramp 98 and is in contact therewith. The hinge plate and hinge post are held against one another by the force exerted by the pitch pin and yaw pin on their respective mating surfaces. Specifically, compression spring 142 which acts on pitch pin 128 presses said pin against ramp 98 while the compression spring in sleeve bottom 118 which acts on yaw pin 146 presses said pin against yaw socket 102.

The forward pitch release setting is determined (the slope of the ramp being fixed) by the force exerted by pin 128 on ramp 98. This force is a function of the compression of spring 142 with the compression of said spring being controlled by the position of externally threaded collar 138 in top sleeve 120. The greater the force exerted by pin 128 on ramp 98 the greater the amount of forward pitching torque required to effect release and vice versa.

The yaw release setting is determined (the slopes of the sides of the socket being fixed) by the force exerted by pin 146 on yaw socket 102 which is determined by the compression of the spring in sleeve 118 with the amount of compression of said spring being controlled in a similar fashion to the manner in which the compression of spring 142 is controlled. The greater the force exerted by pin 146 on socket 102 the greater the yawing torque required to effect release and vice versa.

The rearward pitch release setting is a function of the combined forward forces exerted by both pins 128 and 146.

With the yaw and pitch release settings as just described during controlled skiing the weight of the skier is supported on low friction bearing 40 which rests on ski plate 28 and low friction rollers 76 and 78 which rest on bearing surface 66 and are free to roll thereover. As a result of the above-described arrangement of supporting a skier during skiing, the effect of friction on release settings is minimized under various conditions such as weighted and unweighted falls and intermediate combinations thereof. Moreover, by having bearing 40 approximately beneath the center of gravity of a skier force couples resulting from acceleration forces and the skier's weight are minimized during forward pitching as will hereinafter be described.

Compressible filler material 17 and the side flanges which depend downwardly from sole plate 16 cooperate with each other to reduce entry of snow and/or ice between the ski and sole plate where they would limit the freedom of movement of the sole plate in pitch and yaw. Particular attention is directed to the freedom of downward movement of the front of the sole plate in forward pitching due to the absence of any fixed rigid structure under the sole plate forward of the hinge post and within the angle of forward pitch release.

If the skier should tend to pitch in a forward direction a slight amount and creates a low forward pitching torque the force exerted on ramp 98 by pin 128 will prevent the ski boot from rotating in a forward direc-

tion. It is to be appreciated that as soon as the skier pitches in a forward direction substantially all of his weight is supported on bearing 40 which is positioned beneath his center of gravity so that the effect of his weight on the forward pitch release setting is minimized. If the pitching torque increases above the level selected to effect pitch release, boot 10 and sole plate 16 rotate in a counter clockwise direction as viewed in the FIGS. The pitching rotation takes place about a pitch axis which is horizontal and perpendicular to the length of the ski. The pitch axis shifts rearwardly slightly during forward pitch rotation. Such rotation can be best described by considering hinge plate 30 in terms of its mechanical functional equivalent which is a vertical circular cylinder unitary with and pendant from the sole plate and the forward half of which is nose 34. In the second position, the sides of the nose are in contact with walls 50 and 54 and the bearing at the bottom of the cylinder rests on ski plate 28. Thus, in effect, the boot and sole plate are in unstable equilibrium above the ski plate (and ski) resting on the ski plate and being stabilized by the forward pressure of pin 128 forming the cylinder against and into the bearing angle. When forward pitching rotation occurs several things transpire concurrently. The rear of sole plate 16 lifts while the front portion thereof depresses. Nose 34 tips so that bearing 40 tips and slides rearwardly while top surface tip slides downwardly. As the nose tips the front edge of bearing 40 rests on ski plate 28 and the dual line contact of the cylinder in the bearing angle changes to downwardly moving dual point contact. As the tilting occurs, clearance is created between top surface tip 32 and overhang 57.

If prior to pitch rotation top surface tip 32 is in contact with the overhang and one side of nose 34 is in contact with one of the bearing walls 50,54 (the first position), the initial result of forward pitch rotation is that tip 32 drops below overhang 57. Thereafter both sides of nose 34 contact both walls 50,54 and pitching proceeds as described with respect to the second position.

Pitch release occurs when pin 128 rides off ramp 98. It should be noted that the cooperation of a pin 146 and yaw socket 102 is insignificant insofar as forward pitch release is concerned since the friction resulting from the contact between said pin and walls 102a and 102b is minimal and as pitch release is effected pin 146 passes through the opening at the bottom of yaw socket 104. The slope of yaw socket is such as not to inhibit pitch release. When pin 128 rides off of ramp 98 the boot is free to pitch forwardly. The boot and sole plate are jointly released from the ski plate except for the lanyard. The compressible strip under the front of the sole plate is compressed during forward pitch release. During forward pitch, release pin 128 is forced rearwardly, compressing its associated spring 142.

If the skier should subject the binding to more than a predetermined amount of rearward pitching torque hinge plate 30 moves rearwardly by camming of sloped tip 32 on the matchingly sloped bottom of overhang 57 against the forces exerted by pins 128, 146 until tip 32 clears overhang 57 thereby releasing the plate from the post. Thereafter rearward pitching causes the sole plate to pivot about rollers 76 and 78 with bearing 40 raising from ski plate 28 and top surface tip 32 clearing overhang 57.

If counter clockwise yawing torque is present with nose 34 in contact with walls 50 and 54 and bearing 40 in contact with ski plate 28, hinge plate 30 is urged to rotate in a counter clockwise direction about yawing axis C looking down at said hinge post. Pin 146 applies a torque to yaw socket 102 on wall 102b resisting said rotation. If the yawing torque is sufficient sole plate 16 will rotate in a counter clockwise direction and as said sole plate rotates wall 102b rides over pin 146 compressing the spring in sleeve 118 which compression results in pin 146 increasing the torque resisting yawing. If the yawing torque is sufficiently high, release is effected with pin 146 riding out of socket 104. The friction resulting from the contact between pin 128 and ramp 98 is so insignificant that it does not affect yaw release.

It should be noted that when yawing occurs rollers 76 and 78 roll over surface 66 and hinge plate 30 is supported on low friction bearing 40 so that friction has extremely little effect on the yawing. Further, by having shafts 72 and 74 inclined as previously described, when yawing occurs the rollers follow an arc the center of which is located approximately at C so that the rollers are free to rotate and sliding between said rollers and surface 66 is prevented.

If counter clockwise yawing torque is present in the second position with top surface tip 32 in contact with overhang 57 and one segment of nose 34 in contact with wall 50, then yawing axis C, which is at the center of curvature of nose 34, will be slightly to the side and rear of where it would be if opposed segments of nose 34 were in contact with walls 50 and 54.

When yaw release is complete, lanyard 62 prevents ski 12 from moving away from the boot, with the force exerted by the lanyard on sole plate 16 resulting in a force applied to the portion of the skier's foot best able to resist a pulling strain. Additionally, the lanyard attachment to the center of sole plate 16 enables the ski to clear the boot heel and toe with a lanyard of a minimum length.

By using low friction bearing surfaces to support the skier and small areas of contact between the hinge plate and hinge post, friction does not substantially affect release settings, overcoming a drawback with some prior art bindings. Further, by having bearing 40 beneath the center of gravity of a skier the skier's weight and force couples do not significantly effect release from forward pitching.

Additionally, by eliminating a toe obstruction as part of the release mechanism and binding there is no chance of a skier being injured as a result of his boot catching on said obstruction subsequent to the binding releasing the ski.

In FIGS. 9 through 13 a second embodiment of the present invention is shown and in all embodiments of the present invention identical parts are identified by the same reference numeral.

Permanently and rigidly secured to sole plate 16 on the bottom thereof is a downwardly extending rigid metal hinge plate 200 which includes a forward flat top surface 202, a semi-cylindrical upright front nose surface 204, a flat bottom surface 206 and an upwardly and rearwardly sloping back surface 208. The axis C of curvature of nose 204 defines a yawing axis. Hinge plate 200 is substantially triangular in plan and includes rearwardly flared side surfaces 200a and 200b. A small, e.g., three-eighths inch by 3/8 inch, step bearing 210 is

located on the bottom of surface 206 and normally is in face to face contact with ski plate 28. The top of hinge plate 200 above surface 202 is secured to sole plate 16 in a position such that bearing 210 is approximately beneath the center of gravity of a skier wearing boot 10.

An upstanding rigid metal hinge post 212 is secured to ski plate 28. Hinge post 212 includes a V-shaped rearwardly facing recess 216 which is defined by walls 218, 220, 222 and 224 with walls 218 and 222 and walls 220 and 224 being, respectively, in transverse registry with each other. Walls 218 and 222 are of the same height. Walls 220 and 224 similarly are equal in height with the latter two walls 220 and 224 having a slightly greater height than walls 218 and 222. Recess 216 is bisected by the central longitudinal axis of the ski.

The entry angle of recess 216 defined by walls 218 and 222 is considerably larger than the bearing angle of said recess defined by walls 220 and 224, the amount of excess not being material to proper functioning of the binding. The bearing angle between walls 220 and 224 is, in turn, greater than the angle defined by side surfaces 200a and 200b of hinge plate 200 for that position of the hinge plate extending rearwardly of nose 204 and adapted to be located between the sides of the entry angle. The width of recess 216 at the rear of the entry angle is slightly, e.g., a few thousandths of an inch, wider than the width of nose 204 (twice the radius of curvature of the nose) so that the nose can be seated (received) in the bearing angle for a short distance forwardly of its open rear end, thereby enabling the walls 218 and 222 of the bearing angle to function as bearing surfaces each having a vertical line contact with nose 204. Thus nose 204 is rotatably supported by the bearing angle for turning movement about axis C which constitutes the yaw axis for boot 10. The bearing angle is sufficiently larger than the angle between the side surfaces of the hinge plate to permit the hinge plate, and therefore the boot, to swing right or left with respect to hinge post 212 an angular amount sufficient to release the binding in yaw as hereinafter described without the side surfaces of the plate touching walls 220 and 224 and thereby preventing restriction of such swinging movement.

A rounded wall 226 connects walls 200 and 224 of the bearing angle at the apex of recess 216. An overhang 227 covers recess 216 and extends over the bearing angle and partially back over the entry angle formed by the walls 218 and 222. The bottom of overhang 227 is flat and parallel to ski plate 28. The space between overhang 227 and ski plate 28 slightly, e.g., by 0.003 inch, exceeds the height of nose 204 between top surface 202 and step bearing 210. Overhang 227 extends rearwardly for a short distance, e.g., 1/16 inch, beyond axis C so that when hinge plate is resiliently urged forwardly into recess 216 only a slight vertical play can be experienced by hinge post 212 with respect to hinge plate 200.

A block 234 is secured to the rear of flange 26 and includes a protruding overhand 236 beneath which is formed a socket 238 that is situated at a vertical level between top surface 202 and step bearing 210. Socket 238 is located on the fore-and-aft center line of sole plate 16.

Extending upwardly from ski plate 28 at the sides thereof behind the adjacent block 234 are flanges 242

and 244 which are identical to each other and in mutual registry. A further flange 246 extends between the rear edges of flanges 242 and 244 and includes a central opening 248 for a reason that will soon be readily apparent.

Secured to ski plate 28 and extending upwardly therefrom is a guiding member 250 which includes a channel 252 that is parallel the longitudinal central axis of ski 12. A thrust member 254 includes a depending rod 256 which has a bearing on the bottom thereof with the lower portion of said rod slidably received in channel 252. Secured to the central portion of thrust member 254 and extending forwardly therefrom is an arm 258 which is rounded on its free end with said free end being received in socket 238. Located on the side of thrust member 254 opposite arm 258 and at the same horizontal lever is a U-shaped transverse channel 260 with upper and lower portions of said channel defined by upper side 262 and lower side 264. Spaced partitions 266 and 268 having pointed free rear ends extends vertically between sides 262 and 264 and define a central socket 270. Projecting upwardly from the upper surface of side 262 is a rod 272 tipped by a ball 278 at the uppermost portion thereof.

20 A bail 279 is provided and includes a socket on the bottom portion of the cross piece thereof. Ball 278 is received in the socket on bail 279 and bail sides 280 and 282 are secured to the frontmost portion of flanges 242 and 244. Ball 278 is retained for swivelling movement in bail socket by a split anti-friction washer 274 and a C-ring 276.

30 A dog retaining member 286 includes a generally transversely disposed U-shaped channel 288 bisected by a vertical wall 290. Extending forwardly from the free edge of wall 290 is a rod 292 tipped by a ball 293 at its free end. Ball 293 is received in socket 270 and cooperates therewith in a manner which will soon be readily apparent. An opening extends transversely 40 through wall 290. Located in channel 288 on opposite sides of wall 290 are dogs 292 and 296. A bolt 298 having notched ends extends through the opening in wall 290 with the central portion of said bolt being unthreaded. Flanges (one of which is a C-ring) are secured to the bolt central portion on opposite sides of wall 290 to prevent the bolt from axially moving relative to wall 290. The portions of bolt 298 adjacent the different sides of wall 290 are threaded in opposite directions.

45 Dogs 294 and 296, which are mirror images of each other, each include a threaded opening with the threaded opening of each dog being in mated engagement with the associated portion of bolt 298 and adjacent a different side of wall 290. Since the dogs are mirror images of each other only one needs to be described. Dog 294 includes a block 300 received in and having a cross-section matching that of the channel 288 in which it is received for transverse slidably movement. A yaw arm 302 forming part of block 300 projects outwardly from the channel. Yaw arm 302 includes vertical sides 302a and 302b with the intersection of said sides defining a front bearing edge 302c. Yaw arm 302 is rockably received within channel 260 adjacent the left side of wall 268 as can be seen in FIG. 10. Extending away from the rear surface of dog retaining member 286 in a collar 306 which includes a rearwardly facing hollow opening.

A bolt 308 extends horizontally and slidably through opening 248 and is pivotable therein with the head of said bolt being adjacent and spaced from the rear surface of flange 246. Slidable on bolt 308 is a collar 310 which includes a spring retaining rim 312. A helical compression spring 314 surrounds bolt 308 and has one end in contact with rim 312. A second collar 316 slidable on bolt 308 is provided and surrounds bolt 308 and includes a spring retaining rim 318 with the opposite end of spring 314 in abutment therewith. A nut 320 is provided in contact with the left portion of collar 316 and is in threaded engagement with the left portion of bolt 308. The extreme left end of bolt 308 includes a thrust element 322 received in collar 306.

In the following description of the use of the ski binding just described reference will be made to the operation of one such binding for purposes of brevity, realizing of course that in normal use a skier would use similar bindings for both of his skis.

Lanyard 62 is secured to the means which comprise lanyard supports 58 and 60. Sole plate 16 is positioned so that hinge plate 200 is received within recess 216 with bearing 210 resting on ski plate 28 and nose 204 of the hinge plate resting against walls 220 and 224 beneath overhang 227. Toe of boot 10 is slipped under nose catch 18.

The sole plate is positioned parallel to the ski plate with the two plates spaced apart by the hinge plate. The plates are held in their position by the pitch and yaw release mechanisms described above. Specifically, compressed spring 314 presses forwardly against channel 288 which presses ball 293 against socket 270 and the dog arms against channel 260. In turn, arm 258 presses against socket 238 so as to prevent yawing and/or pitching movement thereof (and of the sole plate and boot) unless and until yaw and/or pitch torques exceed yaw and/or pitch release settings.

The pitch release setting is determined by the force exerted by arm 258 in socket 238. This is a function of the force exerted by thrust element 322 in collar 306 against channel 288. To increase this force nut 320 is rotated so as to increase the compression of spring 314 which increases the force exerted by thrust element 322 on channel 288.

The yaw release setting is determined by the spacing of dogs 294 and 296 from wall 290 which position is controlled by rotation of bolt 298 and by the force exerted by arm 258 in socket 238 which is a function of the force exerted by thrust element 322 on collar 306. When dogs 294 and 296 are as close to each other as possible by rotating bolt 298 in one direction a maximum amount the yawing torque required to effect release is the lowest possible value for a given force exerted by thrust element 322 on collar 306 and as the dogs are moved further away from each other by rotation of bolt 298 with the value of the force exerted by element 322 on collar 306 kept constant the level of yawing torque required to effect release is increased.

With the yaw and pitch release settings as just described during controlled skiing the weight of the skier is supported on bearing 210 which rests on ski plate 28 and thus minimizes frictional surfaces that were common in the prior art which destroyed the integrity of release settings under various conditions such as weighted and unweighted falls and intermediate combinations thereof. Moreover, by having bearing 40 approximately beneath the center of gravity of a skier

force couples resulting from acceleration forces and the skier's weight are minimized thus overcoming one of the drawbacks of the prior art.

If the skier should tend to pitch in a forward direction 5 a slight amount and create a low forward pitching torque the force exerted socket 238 by arm 258 will prevent the ski boot from rotating in a forward direction. If the forward pitching torque increases above the level selected to effect pitching release boot 10 and 10 sole plate 16 rotate in a counter clockwise direction as viewed in the FIGS. Rotation in pitch takes place about a horizontal transverse pitch axis which is horizontal and transverse to the length of the ski. The pitch axis is perpendicular to the yaw axis and initially intersects 15 the same. It shifts rearwardly slightly during pitch rotation. Such rotation can best be described by considering hinge plate 210 in terms of its mechanical functional equivalent which is a vertical circular cylinder unitary with and pendant from the sole plate and the 20 forward half of which is nose 204. The step bearing 210 at the bottom of the cylinder rests on ski plate 28 and the front of the cylinder is pressed against the bearing angle of recess 216 by spring 314, the top of the cylinder being under overhang 227. Thus, in effect, the boot and sole plate (and skier) are in unstable equilibrium 25 above the ski plate resting on small bearing 210, being stabilized by forward pressure of spring 314 forcing the cylinder against and into the bearing angle. When pitch rotation occurs several things transpire concurrently. 30 Socket 238 lifts while the toe of the boot depresses. Nose 204 tips so that bearing 210 tips and slides rearwardly while top surface 202 slides down. As nose tips only the front edge of bearing 210 rests on ski plate 28 and the dual line contact of the cylinder in the bearing angle changes to downwardly moving dual point contacts. Said tilting is permitted by the clearance between top surface 202 and overhang 227.

Pitch release occurs when arm 258 rides out of socket 238. This releases the pressure of spring 314 that urges the hinge plate against the hinge post. Thereupon the boot is free to pitch forwardly, top surface 202 sliding under and then clear of overhang so that the boot and sole plate are jointly released from the ski plate, except for the lanyard. The compressible strip under the front of the sole plate is compressed during pitch release. During pitch release arm 258 is forced rearwardly, in turn forcing channel 288 rearwardly and further compressing spring 314.

If yawing results so that ski boot 10 and sole plate 16 45 rotate about yaw axis C in a counter clockwise direction looking down at said boot then a torque is applied to arm 258 urging the arm to follow the movement of socket 238. Arm 258 and thrust member 254 rotate in a clockwise direction looking down at FIG. 13 with ball 278 rotating in the socket in bail 279. Thrust element 322 in collar 308 prevents substantial rotation of dog retaining member 306 and the rotation of thrust member 258 is about the bearing edge of dog 296. The torque resisting this rotation is the force exerted by thrust element 322 on collar 306 times the perpendicular distance from the vector of said force to the bearing edge of dog 296. If the yawing torque is sufficiently high or the torque resulting from the force exerted by thrust element 322 sufficiently low arm 258 is not able to prevent further rotation of sole plate 16 and release is effected by movement of arm 258 sidewise out of socket 238 freeing sole plate 16 from ski plate 238 ex-

cept for the lanyard connection. It will be appreciated that varying the spacing between the dogs varies the ratio of yaw release to pitch release to vary yaw release without affecting pitch release.

When release is complete the lanyard prevents ski 12 from moving away from the boot with the force exerted by the lanyard on sole plate 16 resulting in a force applied to the portion of the skier's foot best able to resist a pulling strain. Additionally, the lanyard attachment to the center of sole plate 16 enables the ski to clear the boot heel and toe with a lanyard of a minimum length.

A particular feature of the embodiment of the invention just described which merits specific attention is the use of step bearing 210 to support the weight of the skier. As a result of the bearing having a relatively small surface area friction minimally affects yawing and thus does not in any way destroy the integrity of yaw release settings. Also, by having bearing 210 approximately beneath the center of gravity of a skier the weight of the skier does not affect pitch release settings as was quite common with prior art bindings.

In FIGS. 14 through 17 a third ski binding according to the present invention is shown and includes rigidly secured to sole plate 16 a metal hinge plate 400 with said hinge plate extending downwardly away from said sole plate. Hinge plate 400 includes an inclined top surface 402, a rounded upright semi-cylindrical front nose surface 404 and an inclined rear surface 406. The center C of rounded surface 404 defines a yawing axis and the hinge plate is triangular in plan and has side surfaces 400a and 400b which flare outwardly going away from said nose surface. A small rounded step bearing 408 is located at the bottom of hinge plate 400 and the hinge plate is positioned so bearing 408 is approximately beneath the center of gravity of a skier wearing boot 10.

Projecting upwardly from ski plate 28 is a rigid metal hinge post 410 which includes a rearwardly opening V-shaped recess 411 in which hinge plate 400 is normally received. Hinge post 410 includes walls 412a and 412b and walls 414a and 414b which define recess 411. Walls 412b and 414a are equal in height and are in registry with each other while walls 412b and 414b are likewise equal in height but of a greater height than walls 412a and 414a. Walls 412a and 412b define an included obtuse angle which is identical to the included obtuse angle defined by walls 414a and 414b. Walls 412b and 414b define a bearing angle that rotatably receives nose 404 in the same manner as described with respect to the second embodiment. A rounded wall 416 extends upwardly at the apex of recess 411 from ski plate 28 to an upper inclined surface 420 and a bearing 421 is located on the upper portion of edge 420. When sole plate 16 is parallel to ski plate 28 with hinge plate 400 received in recess 411 during controlled skiing surfaces 420 and 402 define a small included angle therebetween (FIG. 24) with surface 420 overhanging surface 402.

Secured to flange 26 is a ski boot release control 434 which is the same height as flange 26. Located on a rear surface 436 of control 434 is a socket 438 for a purpose that will soon be readily apparent. Socket 438 is directly in back of nose 404 and at a horizontal level between the top and bottom of said nose.

Secured to ski plate 28 slightly to the rear of control 434 is a four-sided cup-shaped member 440 having a

base 441. Cup-shaped member 440 includes sides 442, 444, 446 and 448 with sides 444 and 448 being parallel to each other and perpendicular to sides 442 and 446 while sides 442 and 446 are parallel to each other and perpendicular to the remaining sides. It is to be appreciated that while sides 442 and 446 are identical and have varying heights this is optional and said sides could be of constant height. Side 448 acts as a reaction member as will hereinafter be apparent and includes a symmetrical central opening.

A ball 450 is provided which is seated in socket 438 during controlled skiing and a thrust member 452 extends from the rear thereof and through the opening in side 448. It should be noted that the opening in side 448 is at the approximate mid-portion thereof to allow thrust member 452 to have the required freedom of motion when ski boot 10 pitches and/or yaws as is described hereinafter in detail.

Secured to a rear flat surface 454 (see FIG. 25) of thrust member 452 is a vertical plate 456 which includes four edges 458, 460, 462 and 464. An inverted U-shaped opening 466 extends from the bottom edge 462 of plate 456 to the approximate mid-section thereof. Holes 468 and 470 are located in sides 442 and 446 in registry with each other and in registry with the bottom of inverted opening 466.

An L-shaped dog retaining plate 472 has horizontal side 474 secured to the rear portion of top edge 458 of plate 456 and vertical side 476 secured to rear edge 460 of plate 458. A conical socket 478 is located on the rear surface of vertical side 476 and is in the plane of plate 456.

A bolt 480 includes a non-threaded central journal portion 482 with flanges 484 and 486 located on opposite sides of said central portion. The bolt is in registry with holes 468 and 470 and extends through opening 466 with flanges 484 and 486 in contact with opposite sides of plate 456. The central portion of the bolt is positioned at the closed end of opening 466. The left portion 488 of bolt 480 is threaded and the right portion 490 is likewise threaded with the threads on portions 488 and 490 being in opposite directions. Screwdriver receiving notches are located on the free ends of bolt 480 and access thereto is provided through holes 468 and 470.

A left dog 492 is provided and includes a tapped opening 494 which extends through the approximate mid-portion thereof with portion 488 of bolt 480 extending therethrough and in threaded engagement therewith. Dog 492 includes a vertical front side 496 having intersecting vertical surfaces 498 and 500 with the intersection of said surfaces defining a yaw bearing edge 502. Located on the bottom most portion of dog 502 is a pitch bearing 504 which is rounded and shaped to be in rotatable contact with the rounded intersection of the base of cup-shaped member 440 and front side 448 for a reason that will soon be readily apparent.

A right dog 505 is provided and has a tapped opening which is in threaded engagement with portion 490 of bolt 482. Dogs 492 and 505 are mirror images of each other and are symmetrically positioned with respect to plate 456.

An opening extends through rear side 444 of cup-shaped member 440 being symmetrically positioned with respect to sides 442 and 446 and in line with the opening in front side 448. A threaded bolt 506 extends through the opening in side 444 and has a head 508

which is located adjacent but spaced from the rear surface of side 444. A collar 510 surrounds the portion of bolt 506 adjacent the forward surface of side 444 and has a rim 512 adjacent side 444 larger than the opening in side 444 that acts as a spring retaining member. Collar 510 can move axially along bolt 506 and during skiing when there is no movement of sole plate 16 from pitch and/or yaw rim 512 has one side in face-to-face contact with side 444.

A collar 516 also surrounds bolt 506 with a spring retaining rim 518 secured to the left portion of collar 516. Collar 516 can move axially along bolt 506. A nut 520 is threaded on bolt 506 and contacts the front side of rim 518. A compression spring 521 encircles bolt 506, portions of collars 510 and 516 and has one end seated against rim 518 and the other end seated against rim 512.

Integral with the leftmost end of bolt 506 is a thrust rod 522 with the left end of said rod being conically shaped and seated in socket 478, the latter having a greater apex angle. The opening in side 444 has a larger cross section than bolt 506 and a smaller cross section than head 508 and rim 512 so that bolt 506 has freedom to pivot with respect to side 444 but cannot be pulled therethrough.

In use of the binding the lanyard is secured as previously described. Sole plate 16 is positioned so that hinge plate 400 is received in recess 411 (FIGS. 14a) with nose 404 spaced from wall 416 and in dual linear rotatable contact with walls 412b and 414b of the bearing angle. The front of the sole of boot 10 is under and held down by nose catch 18. Heel stop 22 is positioned on the rear of boot sole 14 and the bent ends of arms 24 are placed in registered holes on sole plate 16 with the particular holes selected depending on the length of sole 14. Heel stop then is manually pressed against the rear of the boot sole.

The pitch release setting is determined by the force exerted by thrust rod 522 via plates 472, 456, thrust member 452 and ball 450 on socket 438. Specifically, the greater the force exerted by ball 450 on socket 438 the larger the amount of pitching torque required to effect release and vice versa. The force exerted by thrust rod 522 on socket 478 which controls the force exerted by ball 450 on socket 438 can be varied by rotating nut 520. The further rim 518 is positioned from the conical end of thrust rod 522 the greater the force exerted by spring 521 against rim 518 and the greater the force exerted against socket 508 by said thrust rod while the converse is true.

The yaw setting is determined by the position of dogs 492 and 505 relative to each other which position is controlled by rotation of bolt 480 and the force exerted by thrust member 454 on socket 438. Rotation of bolt 480 in one direction moves the dogs towards each other while rotation of the bolt in the opposite direction moves the dogs away from each other. Specifically, when dogs 492 and 505 are as close to each other as possible the yawing torque required to effect release will be the lowest possible value for a given force exerted by thrust rod 522 and as the dogs are moved further away from each other the value of yawing torque required to effect release is increased as will hereinafter be specifically described in detail. Varying spacing between the dogs varies the yaw to pitch release ratio.

With the yaw and pitch release setting as just described abd ski boot 10 secured to ski 12 the skier is now ready for skiing. During skiing the nose of hinge plate 400 is received in recess 411 with the nose bearing against walls 412b and 414b. The weight of the skier is supported on bearing 408 which rests on the ski plate and thus substantially reduces frictional surfaces that were common in the prior art and destroyed the integrity of release settings. By having bearing 408 approximately beneath the center of gravity of a skier force couples resulting from acceleration forces and the skier's weight are minimized thus overcoming one of the drawbacks in the prior art.

With no forward pitching torque, ball 450 is seated in socket 438 and thrust rod 522 is parallel to ski plate 28 and in alignment with thrust member 452. If the skier should tend to pitch in a forward direction and create a low forward pitching torque the force exerted by ball 450 in socket 438 will prevent ski boot 10 from rotating in a forward direction. If the forward pitching torque increases above the level required to effect release, boot 10 rotates in a counter clockwise direction as viewed in the FIGS. and socket 438 is elevated to the extent that ball 452 is no longer in engagement therewith. During pitching and after release bearing 408 is elevated from ski plate 28 with surface 402 of hinge plate 400 sliding on bearing 421 until complete release is effected. Prior to release ball 452 is slightly elevated with plate 456, plate 472, and dogs 492 and 505 rotating about dog pitch bearings 504 in a clockwise direction so that socket 478 is lowered and the left end of thrust rod 522 is also lowered since the conical portion thereof is in engagement with socket 478. The rotation of sole plate 16 compresses the filler strip beneath plate 16. When release is completed the lanyard prevents ski 12 from moving away from the boot with the force exerted by the lanyard on the sole plate 16 resulting in a force on the strongest portion of the skier's foot.

If the skier tends to yaw so that ski boot 10 is urged to rotate in a counter clockwise direction looking down at said boot (FIG. 16) then a torque is applied to ball 450 urging said ball to follow the movement of socket 438. If the torque is sufficient boot 10 rotates about the yawing axis with the nose of the hinge plate rotating in the bearing angle until release is effected. Thrust member 452, plate 456, plate 472, bolt 480 and dogs 492 and 505 rotate in a clockwise direction looking down at FIG. 16 with bearing edge 502 of left dog 492 pivoting against the inside surface of side 448 and forming a pivot for said rotation. The torque resisting said rotation is the force exerted by thrust rod 522 against socket 478 times the perpendicular distance from the vector of said force to edge 502. If the torque caused by thrust rod 522 is sufficiently high (or the yawing torque is sufficiently low) ball 450 will not release from socket 438 and the amount of yawing of boot 10 will be limited.

If the yawing torque is sufficiently high then the torque resulting from thrust rod 522 does not maintain ball 450 in socket 438 and thrust member 452, plate 456, plate 472, bolt 480 and dogs 492 and 505 pivot laterally about edge 502 until release takes place by socket 438 riding off ball 450.

As noted, the torque resisting yaw release is determined by the magnitude of the force exerted on socket 478 by thrust rod 522 times the perpendicular distance from the vector of said force to either edge 502 on dog

492 or the corresponding edge of dog 505 depending on the direction of yaw and it can be seen that the further the dogs are apart from each other the greater said distance is and conversely the closer the dogs are to each other the smaller the distance is. Thus, it is readily apparent that it is the distance between said dogs plus the degree of compression of spring 521 which determines the force exerted by rod 522 controls yaw release.

The fourth embodiment of the invention illustrated in FIGS. 18-21 utilizes the same pitch and yaw control release structure (parts 434, 440, 452, 456, 474, 480, 492, 505, 506, et seq.) as that previously described in connection with the third embodiment of the invention and differs only from said third embodiment of the invention by the manner in which ski boot 10 (sole plate) is supported on the ski plate. In the fourth embodiment of the invention a vertical trunnion 600 is secured to ski plate 28. A base plate 601 is in contact with ski plate 28. A latch plate 602 is rotatable about the trunnion and includes an interior circular opening 604 which extends from the bottom thereof to the approximate mid-section thereof. Latch plate 602 includes a raised central bearing-defining section 606 having at its uppermost portion a rounded bearing 608. Trunnion 600 is located on ski plate 28 in a position such that when ski boot 10 is secured to ski 12 bearing 608 will be approximately beneath the center of gravity of the skier.

Extending about the base of bearing-defining section 606 is a plate 610 which extends slightly to the front of trunnion 600, surrounds said trunnion and extends a small distance rearwardly of the heel of sole 14. In this embodiment of the invention flange 26 extends downwardly a sufficient amount so as to contact and rest on the rear portion of plate 610.

Raised section 606 slopes downwardly from bearing 608 going from left to right of said structure as viewed in the FIGS. and a lip 612 extends inwardly therefrom to a vertically depending edge 614.

A tang 616 is secured to sole plate 16 and includes edges 618, 620, 622. Edge 618 is slightly bowed and extends downwardly from sole plate 16 while edge 622 which is straight also extends downwardly from sole plate 16. Edge 620 extends between the portions of edges 618 and 622 furthest from sole plate 16. Secured to the rear of flange 26 is the pitch and yaw control which cooperates with the pitch and yaw release mechanism as previously described.

During controlled skiing sole plate 16 rests on bearing 608 with the lower portion of edge 618 hooked beneath lip 612 of latch plate 602. Thus, the entire weight of the skier is supported by latch plate 602 at bearing 608 and on the rear of plate 610 where flange 26 contacts said plate which plate is integral with said latch plate. As a consequence thereof no frictional surfaces are created that result in torques affecting the pitch and/or yaw release settings.

If excessive forward pitching torque occurs the toe of boot 10 not being restrained moves closer to ski 12 and the sole plate rotates about bearing 608 in a clockwise direction until tang 616 is no longer hooked under latch plate lip 612 and release is effected. The operation of the pitch release mechanism is as previously described. It should be noted that by having the skier's weight supported at approximately the center of gravity pitch release is independent of acceleration forces and no frictional bearing surfaces are present which can

change the apparent setting of the pitch release torque. If the forward pitching torque is created insufficient to effect release ball 452 remains in socket 458 and sole plate 14 remains parallel to ski plate 16.

If sufficient yawing torque occurs latch plate 602 rotates about trunnion 600 rotating the ski boot with ball 450 resisting said rotation. If the yawing torque is sufficiently low then release is not effected while if the yawing torque is sufficiently high ball 450 disengages from socket 438 as previously described.

In all embodiments of the present invention it is important to note that acceleration forces, the skier's weight and force couplings do not affect release settings. Additionally, yawing friction is minimized since the skier's weight is secured by bearing means which assists in maintaining the integrity of the yaw release settings. A further feature of the present invention which deserves special note is that the torque required to effect pitch release can be varied independently of the torque required to effect yaw release and vice versa, something that was not possible with many prior art ski bindings.

An additional feature of the invention worthy of special note is that the toe portion of the sole plate has freedom of movement relative to the ski and no toe obstructions are present to hamper proper release as occurred in the prior art.

It thus will be seen that there are provided ski bindings which achieve the various objects of the invention and which are well adapted to meet the conditions of practical use.

As various possible embodiments might be made of the above invention, and as various changes might be made in the embodiments above set forth, it is to be understood that all matter herein described or shown in the accompanying drawings is to be interpreted as illustrative and not in a limiting sense.

Having thus described the invention there is claimed as new and desired to be secured by Letters Patent:

1. A ski element having an upper surface, a boot element having a lower surface, means located approximately beneath the center of gravity of a skier and intermediate the length of said boot element and intermediate the length of said ski element for mounting said boot element to said ski element and providing a fulcrum so the boot element can pivot with respect to the ski element about a forward pitching axis and a yawing axis, settable release means for forming a releasable connection between the ski element and the rear of the boot element for releasing said boot element from said ski element, said mounting means maintaining a space between the portion of said ski element upper surface forward of said mounting means and the portion of said boot element lower surface forward of said mounting means when said release means forms said connection between the rear of said boot element and said ski element, said forward pitching axis and said yawing axis substantially mutually intersecting between the upper surface of the ski element and the lower surface of the boot element and approximately beneath the center of gravity of a skier when said settable release means forms a releasable connection between the ski element and the rear of the boot element whereby the effect of acceleration forces and a skier's weight are minimized during forward pitching.

2. Apparatus according to claim 1 wherein said mounting means includes low friction means on which the boot element is supported.

3. Apparatus according to claim 2 wherein said low friction means includes bearing means located in such position as to be approximately beneath the center of gravity of a skier.

4. Apparatus according to claim 3 wherein said low friction means includes a member structured to be fixed relative to one of said elements during skiing, said bearing means being located on one portion thereof and means fixed relative to the other of said elements for receiving a portion of said member for rotation about a yawing axis.

5. Apparatus according to claim 4 wherein said receiving means projects upwardly towards the boot element.

6. Apparatus according to claim 5 wherein said receiving means includes means forming a recess for receiving a portion of said member.

7. Apparatus according to claim 1 further including means for preventing ice and/or snow impeding the action of said maintaining means.

8. Apparatus according to claim 1 wherein said mounting means includes a member structured to be fixed to one of said elements, a receiving means for receiving a portion of said member fixed to the other of said elements, said settable release means including means for urging said member into said receiving means.

9. Apparatus according to claim 1 wherein said settable release means includes means for holding the boot element fixed in a predetermined orientation relative to the ski element upon their being less than a predetermined amount of pitching torque and less than a predetermined amount of yawing torque and for releasing the boot element from the ski element responsive to their being more than a predetermined amount of pitching torque and more than a predetermined amount of yawing torque.

10. Apparatus according to claim 1 wherein said settable release means includes force receiving means structured to be fixed relative to the rear of the boot element and means affixed to the ski element for applying a selectively variable force thereto.

11. Apparatus according to claim 10 wherein said force applying means includes at least one force element which applies a force on said force receiving means.

12. Apparatus according to claim 10 wherein said force receiving means includes a pitch control means and said means for applying selectively variable force thereto includes a force element which can apply a settable force on said pitch control means.

13. Apparatus according to claim 10 wherein said force receiving means includes a yaw control means and said force applying means includes a force element for applying a selectively variable force on said yaw control means.

14. Apparatus according to claim 10 wherein said force receiving means includes a member having a socket and said force applying means includes a force element seatable in said socket.

15. Apparatus according to claim 14 wherein said settable release means further includes a thrust member integral with said force element and means in which said thrust member can pivot with said thrust member

transmitting force to said force element, a force transmitting structure connected to said thrust member, and means applying a force to said force transmitting structure which in turn applies a force to said thrust member and force element.

16. Apparatus according to claim 15 further including first and second spaced yaw control elements with said elements each having a yaw bearing, a reaction surface, a yaw bearing of one of said yaw elements always being in contact with said reaction surface and said yaw control elements being fixed to said force transmitting structure.

17. Apparatus according to claim 16 wherein means is provided for moving said yaw control elements simultaneously towards each other and away from each other to vary the distance between said yaw bearings and the vector of the force produced by said force applying means.

18. Skiing apparatus comprising means for securing

20 a boot relative to a ski, said securing means including means for holding a boot in a fixed predetermined orientation relative to a ski upon their being less than a predetermined amount of pitching torque and less than a predetermined amount of yawing torque and for releasing a boot from a ski responsive to their being more than a predetermined amount of pitching torque and a predetermined amount of yawing torque, said holding means including a force receiving means fixed relative to a boot, a force element for applying a force to said 25 force receiving means, a thrust member integral with said force element, means in which said thrust member can pivot and means for applying a variable force to said thrust member, a force transmitting structure connected to said thrust member, control means for applying a force to said force transmitting structure which in turn applies a force to said thrust member and said force element, first and second spaced yaw control elements with said elements each having a yaw bearing, a reaction surface, a yaw bearing on at least one of said 30 yaw control elements always being in contact with said reaction surface and said yaw control elements being fixed to said force transmitting structure, for moving said yaw control elements simultaneously towards each other and away from each other to vary the distance 35 between said yaw bearings and the vector of the force produced by said control force applying means.

19. A ski binding apparatus comprising means for securing a boot element to a ski element and means cooperating with said securing means for maintaining a boot element spaced from a ski element and about which maintaining means a boot element can pivot with respect to a ski element about a forward pitching axis and a yawing axis, said maintaining means being located intermediate the toe and heel of a boot element, said forward pitching axis and yawing axis substantially mutually intersecting between a boot element and a ski element, said maintaining means including bearing means located so as to be approximately beneath the center of gravity of a skier and about which a boot element can be supported, a member structured to be fixed to one of the elements during skiing, said bearing means being located on one portion thereof, receiving means fixed relative to the other of said elements for receiving a portion of said member for rotation about a yawing axis, said receiving means including a recess for receiving a portion of said member, said recess being defined by spaced inclined opposed upright bearing walls

against which a portion of said member rests during controlled skiing.

20. Apparatus according to claim 19 wherein said member includes a nose with said nose being substantially cylindrical and the center thereof defining a yawing axis.

21. Apparatus according to claim 20 wherein said member includes an upper surface and a bottom surface with said nose extending between said upper surface and said bottom surface.

22. Apparatus according to claim 21 further including an upright entry wall integral with each bearing wall at the rear thereof with said entry walls in registry with one another and defining an included angle greater

than the angle between said bearing walls.

23. Apparatus according to claim 20 wherein said member includes a camming means, said receiving means including a bearing surface against which said camming means can be placed in contact during skiing.

24. Apparatus according to claim 23 wherein said receiving means includes an overhang having an under surface with said bearing surface being located on said under surface.

25. Apparatus according to claim 24 wherein said bearing surface of said receiving means and said camming means are parallel to one another during skiing.
